UNITED STATES PATENT OFFICE

90,558

DESIGN FOR A PERFUME BOTTLE

René Tricard, Paris, France, assignor to Lenthalic Incorporated, New York, N. Y., a
Corporation of New York

Application May 12, 1933. Serial No. 48,087

Term of patent 14 years

To all whom it may concern:

Be it known that I, RENÉ TRICARD, a citizen of France, residing at Paris, France, have invented a new, original, and ornamental Design for a Perfume Bottle, of which the following is a specification, reference being had to the accompanying drawing, forming a part thereof,

In the drawing of the perfume bottle:

I claim:

The ornamental design for a perfume bottle substantially as shown.

RENÉ TRICARD.
